[57] CLAIM

The ornamental design for a sports timer, as shown and described.

DESCRIPTION

FIG. 1 is a front elevational view of a sports timer showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof.

The strap partially shown in all figures is understood to be a complete loop of indeterminate length.

FIG.1

FIG. 2
